UNITED STATES PATENT OFFICE.

TULLIE DEAN, OF MAUCKPORT, INDIANA.

SILO.

1,406,942.

Specification of Letters Patent. Patented Feb. 14, 1922.

Application filed May 24, 1920. Serial No. 383,769.

To all whom it may concern:

Be it known that I, TULLIE DEAN, a citizen of the United States, residing at Mauckport, in the county of Harrison and State of Indiana, have invented certain new and useful Improvements in Silos, of which the following is a specification.

This invention relates generally to an improvement in silos, and particularly to a means whereby the ensilage may be taken from the silo at any particular unloading point, and delivered to the ground or surface line.

The invention contemplates the use of a silo having an upright well or chute, as usual, into which the doors of the silo proper open at different points in the height of the silo, the said chute having an outlet door at the bottom. Ordinarily in withdrawing a quantity of ensilage from the silo, the farmer climbs the interior of the chute to the proper door of the silo, and entering the silo, takes the desired quantity therefrom and allows it to drop through the chute, the ensilage accumulating in the chute being taken out through the outlet opening thereof.

The present invention contemplates an elevator operating in the chute through the use of weights which overbalance the weight of the elevator and operator, and are in turn overbalanced by the ensilage delivered to the elevator. The elevator will thus move automatically in both directions, being controlled by a manually operated brake. The elevator has doors opening to the chute outlet, and automatically held opened when the elevator is at the lowermost or discharging position, and automatically held closed in other positions of the elevator. A door is also provided in the elevator which may be arranged opposite any particular silo door to permit delivery of the ensilage from the silo into the elevator.

The invention is illustrated in the accompanying drawings in which:

Fig. 1 is a plan showing the silo and chute with the top of these parts and the elevator omitted.

Fig. 2 is a perspective view of the elevator.

Fig. 3 is a vertical longitudinal sectional view through the chute, showing more clearly the elevator and its parts.

Fig. 4 is a broken fragmentary sectional view, showing more clearly the relation of the hinge section to the silo in a working position.

Fig. 5 is an enlarged detail illustrating the braking means.

In the accompanying drawings is shown a conventional silo 1, having a substantially rectangular well or chute 2 connected to the wall of the silo, the silo doors 3 opening into the chute.

An elevator 4 is arranged to travel vertically within the chute 2, said elevator including a box-like body having side walls 5, a bottom 6, a rear wall 7, and a front wall in the form of doors 8. Guide strips 9 are secured to the side walls of the chute, and cooperating guide ways 10, preferably formed by spaced strips 11 are arranged on each side wall 5 of the elevator, to guide the elevator in its vertical movement.

The elevator is operated by weights 12 which may be disposed beyond the walls of the chute, which weights are connected by cables 13 to the elevator. The cables 13 each pass over spaced guide pulleys 14 mounted in a bracket 15 at the upper end of the chute. The bracket 15 is supported on bars 16 forming terminals of brace rods 17 which extend across the silo proper and are secured in the walls thereof. The weights 12 overbalance the weight of the elevator and the weight of the operator, so that if the elevator contains the operator alone, and is free to move the elevator will rise. A substantial quantity of ensilage however will overbalance the weights, so that when the elevator is loaded, and free to move, it will descend in the chute. Thus the elevator will be caused to automatically ascend with the operator to the loading point, and descend with the load to the discharging point. Controlling cables 18 and 19 are provided whereby the movement of the elevator is manually governed. Cable 18 is connected at one terminal to the floor of the elevator, while cable 19 is connected at one terminal to the bracket 15. The opposite ends of these cables are wound in the same direction about independent drums 20 and 21 respectively formed on a shaft 22, the ends of which shaft are mounted in suitable bearings 23 slidable in slots 24 formed in the sides of a frame 25 secured to the side walls 5 of the elevator, and extending above the same, the cross bar 26 of the frame having a slot 27 to permit the passage therethrough of the controlling cable 19. A brake block 28 is secured to one of the side bars of the frame 25 and formed at 29 to cooperate with a brake drum 30 secured on

100

105

110

a shaft 22. The bearing slots 24 are of such length that when the shaft has been moved toward the upper end of said slots the drum 30 will engage the block 28. A manually operable member is arranged to cooperate with the brake drum and force the latter into braking cooperation with the block 28. This brake controlling member is in the form of a lever 31 pivotally supported intermediate its ends at one end connected with the elevator by an extension spring 33. In advance of the pivot 32, which pivot may if desired be a rocking connection the brake lever 31 is shaped at 34 to conform to the shape of the brake drum, being extended forwardly from such section 34, as at 35 to which a chain or other operating means 36 is connected, said chain depending within the elevator, to be conveniently reached by the operator.

So long as the shaft 22 is locked by the brake, the controlling cables 18 and 19 will of course prevent movement of the elevator by the weights 12, but upon operation of the brake lever 31 to permit the drum 30 to drop from the block 28 the braking action of the shaft is relieved, and the elevator will operate either under the influence of the weights 12 or under the influence of the load in the elevator.

The front wall 8 of the elevator is in the form of doors hinged to the side walls at 37. Springs 38 are connected to the side walls of the elevator and to the doors, so as to open the latter when free to act. The upper ends of the doors are connected to cables 39 guided over pulleys 40 on the elevator structure and depend below the elevator where they are connected to weights 41. When the elevator is in lowered position the weights 41 engage with the bottom of the chute or well, and the doors, relieved of the influence of the weights will automatically open under the influence of the springs 38. As the elevator leaves the bottom of the chute however, the weights 41 act to close the doors, the doors being thus held closed by the weights until the elevator returns to the bottom of the chute. The rear wall 7 of the elevator is provided with an upper hinged section 42 having side plates 43 sliding in guides 44 secured to the side walls 5 of the elevator. The section 42 when opened engages the bottom of a doorway or opening in the silo, such section 42, with the sides 43 forming a chute down which material may be delivered from the silo to the elevator.

If desired a bar 45 may be provided to be arranged in brackets 46 secured to the walls of the chute 2 in such position that as the elevator rises said bar 45 will engage the cross bar 26 of the frame 25. This bar 45 may be arranged opposite any door way of the silo, and form a stop for the elevator in an exactly correct position relative to said

door way, and thus relieve the operator of a particularly accurate operation of the brake mechanism for stopping the elevator at the proper point.

The operation will be apparent from the drawings, it being understood that the operator entering the elevator through the normally opened doors, operates the connection 36 to move the brake lever 31 and thereby permit shaft 22 to revolve. The weights 12 cause the elevator to ascend, the doors 8 closing immediately following the initial upward movement of the elevator. If the bar 45 is used the elevator will stop when engaging the same, or if such bar be not used the operator can control the elevator through the brake lever 31, to stop the elevator at the desired point. The chute section 42 is then opened, the free end of said chute being formed to accurately fit in the doorway of the silo, as at 47 if desired. The operator will then load the elevator from the silo, and on again operating the brake lever 31, the elevator will descend to the discharge opening from the chute 2, at which point the doors 8 of the elevator will automatically open for the removal of the contents of the elevator.

It is to be noted that the bottom of the doors 8 do not reach to the bottom of the elevator, and have leather extensions 50 which overlie and extend slightly below the bottom of the elevator, to seal the juncture against the leakage of the ensilage. The cable 18, within the elevator passes through a pipe 51 secured in position in the elevator and preferably tapering on its lower end. This will prevent the cable from contact with the ensilage. A step 52 is arranged on the inside of the elevator at the rear portion, as indicated in dotted lines in Fig. 2. This will assist the operator in reaching the opening in the silo proper.

The bottom of the elevator is preferably inclined downwardly from the rear toward the front, to facilitate the discharge of the ensilage when desired.

What I claim is:

1. The combination with a silo having a chute, of an elevator mounted for sliding movement in the chute, weights for raising said elevator, controlling cables for governing the movement of the elevator, a shaft mounted in movable bearings about which said controlling cables are wound, and braking mechanism including a manually operable element whereby the shaft through its movable bearings is actuated to and from braking position.

2. The combination with a silo having a chute, of an elevator mounted for sliding movement in the chute, weights for raising said elevator, controlling cables for governing the movement of the elevator, a shaft mounted in movable bearings about which

said controlling cables are wound, a brake drum on the shaft, a fixed brake block to cooperate with said drum, and a manually operable lever whereby the shaft is regulated 5 to govern the braking cooperation between the drum and brake block.

3. The combination with a silo having a chute of an elevator mounted for sliding movement in the chute, cables for raising 10 the elevator, guide rollers for the cables, weights connected to the cables to overbalance the weight of the elevator, a shaft carried by the elevator, controlling cables wound in opposite directions about the shaft, 15 one of said cables being connected to the elevator and the other of said cables being connected to a fixture above the elevator, and means for controlling the movement of the shaft.

20 4. The combination with a silo having a chute of an elevator mounted for sliding movement in the chute, cables for raising the elevator, guide rollers for the cables, weights connected to the cables to overbalance the 25 weight of the elevator, a shaft arranged for limited play and carried by the elevator, controlling cables wound in opposite directions about the shaft, one of said cables being connected to the elevator and the other 30 of said cables being connected to a fixture above the elevator, and means to shift the shaft in its limited play movement to control the movement of the shaft.

5. The combination with a silo having a 35 chute of an elevator mounted for sliding movement in the chute, cables for raising the elevator, guide rollers for the cables, weights connected to the cables to overbalance the weight of the elevator, a shaft carried by the elevator, controlling cables wound in opposite directions about the shaft, one of said cables being connected to the elevator and the other of said cables being connected to a fixture above the elevator, a 40 fixed braking element arranged adjacent the shaft, and a manually operable member to bodily shift the shaft through its limited play to and from cooperation with the braking element.

50 6. The combination with a silo, having a

chute of an elevator operative in said chute, a frame member secured to the elevator and providing a cross bar above said elevator, weight operated means for raising the elevator, a shaft mounted in said frame and 55 having a limited vertical play therein, oppositely wound cables arranged on the shaft, one of said cables being connected to the elevator and the other of said cables connected to a fixture above the elevator, a fixed brake 60 block carried by said frame, and means whereby the shaft may be operated in its mounting frame to and from cooperation with the brake block.

7. The combination with a silo, having a 65 chute of an elevator operative in said chute, a frame member secured to the elevator and providing a cross bar above said elevator, weight operated means for raising the elevator, a shaft mounted in said frame and having 70 a limited vertical play therein, oppositely wound cables arranged on the shaft, one of said cables being connected to the elevator and the other of said cables connected to a fixture above the elevator, a fixed brake 75 block carried by said frame, a lever adapted to cooperate with the shaft to move the shaft into cooperation with the brake block, and a spring for normally holding said lever in shaft braking position. 80

8. The combination with a silo, having a chute of an elevator operative in said chute, a frame member secured to the elevator and providing a cross bar above said elevator, weight operated means for raising the elevator, a shaft mounted in said frame and having a limited vertical play therein, oppositely wound cables arranged on the shaft, one of said cables being connected to the elevator and the other of said cables connected 85 to a fixture above the elevator, a fixed brake block carried by said frame, a lever adapted to cooperate with the shaft to move the shaft into cooperation with the brake block, a spring for normally holding said lever in 90 shaft braking position, and means for manually operating the lever against the influence of its spring. 95

In testimony whereof I affix my signature.
TULLIE DEAN.
